M. M. KRESGE,
SELF ALINING REAMER HOLDER,
APPLICATION FILED MAR. 1, 1920.

Patented Mar. 15, 1921.

Inventor

Miles M. Kresge,

By Foster, Freeman, Watson & Co.,

Attorneys.

UNITED STATES PATENT OFFICE.

MILES M. KRESGE, OF ELMIRA HEIGHTS, NEW YORK.

SELF-ALINING-REAMER HOLDER.

1,371,630.

Specification of Letters Patent. Patented Mar. 15, 1921.

Application filed March 1, 1920. Serial No. 362,544.

To all whom it may concern:

Be it known that I, MILES M. KRESGE, a citizen of the United States, and residing at Elmira Heights, Chemung county, State of New York, have invented certain new and useful Improvements in Self-Alining Reamer Holders, of which the following is a specification.

This invention relates to holders for reaming tools and the like, and its object is to provide a device of that character which will enable the reamer to move in any way necessary to accurately align itself with the work, or in other words, to provide a device which will permit the tool to center itself in the bore of the work axially thereof so that a true cylindrical aperture is produced in the work. To accomplish this object there are provided two members one of which is intended to be secured in a lathe or similar machine and the other having a socket for receiving the reaming tool, these members being yieldingly held in spaced relation and being provided with a pivotal bearing arranged between them so that one member may move in any direction relative to the other member by which accurate alignment of the tool and work may be effected. The invention also contemplates certain improvements in the details of construction as will hereinafter appear.

The invention is shown in one form in the accompanying drawings in which:

Figure 1 is a horizontal sectional view of the holder, parts being shown in elevation;

Fig. 2 is a vertical sectional view of the holder, parts being also shown in elevation;

Fig. 3 is a transverse sectional view on the line 3-3 of Fig. 1 looking in the direction of the arrows.

Referring to the drawings in detail, 1 designates what is termed the supporting member of the holder, this member being provided with a shank 1^a which is adapted to be inserted in a lathe or other machine intended to rotate the same. This member is also provided with a face portion A. Arranged adjacent the supporting member 1 is a socket member 2 of the holder which is intended to receive the reaming tool 3, a set screw 4 being provided for holding the tool in the socket member. The socket member 2 is provided with a face portion B intended to be arranged opposite the face A of the supporting member 1. On the face of the supporting member 1 two bolts 5, 5, are

mounted, these bolts being secured in threaded openings 6 in said member 1. The socket member 2 is provided with openings 7, 7, through which said bolts 5, 5, extend, these bolts constituting means by which the two members are held together and it will be noted that the openings 7, 7, in the member 2 are somewhat larger than the bolts 5, 5, such loose engagement permitting movement of the member 2 relative to the bolts. The member 1 is also provided with two pins 8, 8, which extend a slight distance beyond the face A thereof and are surrounded by coiled springs 9, these springs being adapted to bear against the opposing face B of the member 2. The bolts 5, 5 are arranged on opposite sides of the pivotal center of the face A of the member 1 and the pins 8, 8 are also arranged on opposite sides of the pivotal center of this member so that a line connecting the pins 8, 8 would be substantially at right angles with a line connecting the bolts 5, 5. Near the central portion of its face the member 1 is provided with a recess in which a hardened steel bearing plate 10 is inserted and a similar plate 11 is inserted in a recess of the member 2. The plate 10 of the member 1 is provided with a depression 13 in which a hardened steel ball 12 is placed, this ball constituting a pivotal bearing between the members 1 and 2.

The foregoing construction provides a holder in which the members are mounted in spaced relation and in which a single pivotal bearing point between said members is afforded. When assembled in operative relation the member 2 is movable with reference to the member 1, such movement being permitted by reason of the pivotal bearing heretofore referred to. The springs mounted between said members constitute means which hold the members in alignment but which will yield so as to permit the tool to move in any direction and accurately align itself with the work, the loose engagement between the bolts 5 and the socket member 2 being provided to permit such yielding movement of the socket member 2 with reference to the supporting member 1.

It is apparent that various modifications may be made in the details of the construction herein set forth and it is not to be understood that the invention is limited to such specific details since it is obviously capable of embodiment in other forms differing in specific construction from that described.

Having thus described my invention what I claim as new and desire to secure by Letters Patent is:

1. A holder for a reamer or the like comprising a supporting member having a plane front face, and a socket member having a plane rear face, a series of bolts rigidly secured to one of said members and projecting from the plane face thereof and loosely engaging the other member, for holding said members together, means arranged between said members for holding the same in spaced relation, said spacing means constituting a pivotal bearing between said members, and springs arranged between the plane faces of said members, whereby one member may move relative to the other about said pivotal bearing.
2. A holder for a reamer or the like comprising a supporting member and a socket member, a series of bolts rigidly secured to one of said members and loosely engaging the other member for holding said members together, a ball arranged between said members for holding the same in spaced relation, said ball constituting a pivotal bearing between said members, a series of pins rigidly secured to and projecting from one of said members, coiled springs surrounding said pins and bearing against the other member, whereby one member may move relative to the other about said pivotal bearing.
3. A holder for a reamer or the like comprising a supporting member and a socket member, a series of bolts rigidly secured to said supporting member and loosely engaging openings in said socket member, a bearing plate mounted in each of said members, a ball arranged between said bearing plates,

said ball constituting a pivotal bearing between said members, a series of pins rigidly secured to and projecting from said supporting member, coiled springs surrounding said pins and bearing against the other member, whereby one member may move relative to the other about said pivotal bearing.

4. A holder for a reamer or the like comprising a supporting member and a socket member having juxtaposed faces, means arranged between said faces of said members at substantially the central portion thereof and constituting a pivotal bearing between said members, bolts rigidly secured to one of said members on opposite sides of said pivotal bearing and loosely engaging the other member, pins rigidly secured to one of said members on opposite sides of said pivotal bearing and extending toward the other member, and springs surrounding said pins and bearing against the faces of said members.

5. A holder for a reamer or the like comprising a supporting member and a socket member each provided with a plane face, a ball arranged between said faces and constituting a pivotal bearing between said members, bolts secured to one of said members on opposite sides of said pivotal bearing and loosely engaging the other member, pins secured to one of said members on opposite sides of said pivotal bearings and on a line substantially at right angles with a line connecting said bolts, and coiled springs surrounding said pins and bearing against the faces of said members.

In testimony whereof I affix my signature.

MILES M. KRESGE.
